FIG. 4

FIG. 5

FIG. 6

FIG. 7

FIG. 8

FIGURE 1 is a top plan view of a wallet-check holder combination showing my new design, in unfolded condition with both of the inside leaves overlying the right fold thereof;

FIGURE 2 is a similar plan view of FIGURE 1 with each of the inside leaves overlying the right and left folds, respectively;

FIGURE 3 is a similar plan view of FIGURE 1 with both of the inside leaves overlying the left fold thereof;

FIGURE 4 is a bottom perspective view of the wallet-check holder combination with the inside leaves hanging loosely therefrom;

FIGURE 5 is an end elevational view thereof in slightly unfolded condition; and

FIGURE 6 is an end elevational view thereof in closed and folded condition;

FIGURES 7 and 8 are front and back perspective views thereof in the closed and folded condition illustrated in FIGURE 6.

A transparent card holder and writing instrument are indicated by means of broken lines in FIGURES 1 and 2, respectively, for illustrative purposes only.

I claim:

The ornamental design for wallet-check holder combination, substantially as shown and described.
